UNITED STATES PATENT OFFICE.

CARL R. ALBERTUS, OF CHICAGO, ILLINOIS, ASSIGNOR, BY MESNE ASSIGNMENTS, TO AMERICAN ELECTRIC COMPANY, A CORPORATION OF ILLINOIS.

ELECTRIC BELL OR RINGER.

1,041,943.

Specification of Letters Patent.

Patented Oct. 22, 1912.

Application filed January 17, 1908. Serial No. 411,234.

To all whom it may concern:

Be it known that I, CARL R. ALBERTUS, a citizen of the United States of America, and resident of Chicago, Cook county, Illinois, 5 have invented a certain new and useful Improvement in Electric Bells or Ringers, of which the following is a specification. *

My invention relates to electric bells or ringers, such, for example, as those more 10 commonly used in connection with telephones.

The principal object of my invention is to provide a bell or ringer in which the mechanism for adjusting the gongs relatively to the striker is so located or disposed that it is accessible without entering the usual box or casing by which the electromagnets or other parts of the ringer are usually inclosed.

20 Another object is to provide a simple and improved mechanism for adjusting the gongs of the ringer.

It is also an object to provide certain details and combinations and features of improvement tending to increase the general efficiency of an electric bell or ringer of this particular character.

To the foregoing and other useful ends, my invention consists in matters hereinafter 30 set forth and claimed.

In the accompanying drawings,—Figure 1 is a vertical sectional view on line 1—1 in Fig. 2, showing an electric bell or ringer embodying the principles of my invention, 35 and illustrating the manner in which the adjusting mechanism for the gongs is arranged outside of the box or casing. Fig. 2 is a vertical section on line 2—2 in Fig. 1. Fig. 3 is a detail section on line 3—3 in Fig.

40 Fig. 4 is a detail section on line 4—4 in Fig. 1. Fig. 5 is a perspective of one of the mountings for the gongs.

As thus illustrated, my invention comprises a pair of electromagnets A, a pair of 45 permanent magnets B connected with the cores of said electromagnets, and an upper bracket plate C by which the said magnets are connected together. A polarized armature D is supported on a torsional spring d, which latter is secured to an adjustable yoke 50 d¹ suitably held on threaded posts d². The

said armature carries a rod or arm d³, which latter has a hammer or striker d⁴ at its upper end, the same being disposed between the two gongs E. It will be seen that the 55 bracket plate C is secured to a mounting plate F, which latter is preferably rectangular in form or shape, and secured in any suitable manner to the top or upper surface of the box or casing G, as illustrated. The 60 said mounting plate F is provided with upturned ears or lugs f, a pair of said ears or lugs being disposed at each side of the striker d⁴. In each pair of ears or lugs there is mounted a micrometer adjusting screw 65 f¹, the same being suitably held against endwise movement, but being free to rotate within the bearings provided by the said ears or lugs. The two gong mountings H are formed with feet h, which bear upon 70 and slide along the smooth upper surface of the plate F, and are also provided with downwardly extending portions h¹ having threaded openings h². It will be seen that the screws f¹ extend through the said 75 threaded openings h², so that any rotation of said screws is necessarily accompanied by a traveling movement thereon of the said gong mountings H. Each gong mounting is also provided at its top or summit with 80 an opening h³, in which is secured a post h⁴. It is to the tops of these posts h⁴ that the gongs E are secured by screws h⁵, in the manner shown. The said screws f¹ are provided with slotted heads f², which are adapted 85 to receive a screw driver, whereby the screws are turned for the purpose of adjusting the gongs toward and away from the striker d⁴, in order to obtain the desired results.

90 From the foregoing, it will be seen that the mechanism for adjusting the gongs is located entirely outside of the box or casing by which the magnets of the ringer are inclosed, which box or casing may be that of 95 the ordinary wall telephone. With this arrangement, the prongs can be adjusted without entering the box or casing of the telephone. Furthermore, the micrometer screws are calculated to afford very nice and delicate adjustment for the gongs, thereby insuring the best results.

What I claim as my invention is:

An electric bell or ringer comprising a base plate provided with upturned lugs, axially alined micrometer screws rotatably mounted on said lugs, mountings carried on said screws and provided with feet bearing upon and adapted to slide along the smooth surface of said plate, gongs carried by said

mountings, and means for sounding the gongs.

Signed by me at Chicago, Ill., this 27th day of Nov. 1907.

CARL R. ALBERTUS.
